UNITED STATES PATENT OFFICE.

WILLIAM E. ANDRÉE, OF CHICAGO, ILLINOIS, ASSIGNOR, BY DIRECT AND MESNE ASSIGNMENTS, OF ONE-HALF TO THE AMERICAN LAUNDRY MACHINERY COMPANY, OF NORWOOD, OHIO, A CORPORATION OF OHIO, AND ONE-HALF TO METROPOLITAN TRUST COMPANY, TRUSTEE, OF NEW YORK, N. Y., A CORPORATION OF NEW YORK.

GARMENT PRESS.

Original application filed June 7, 1916, Serial No. 102,296, Patent No. 1,368,684, dated February 15, 1921.
Divided and this application filed December 5, 1919. Serial No. 342,607.

This invention relates to garment pressing machines, such as are used for pressing coats, trousers, vests or other articles of wearing apparel, or even other kinds of 5 articles made of textile fabrics or the like.

The object of the invention is to provide an improved press of this general character having one of its pressing members so arranged as to enable steam for moistening the garment or material to be quickly supplied thereto and the moisture and excess 10 or remaining steam to be quickly and effectively withdrawn from between the pressing members and from an article in 15 pressing position or from the padding of the pressing members themselves.

A further object of the invention is to simplify and improve the construction of the lower pressing member by providing it 20 with a relatively large heating cavity and a relatively shallow chamber beneath a perforated pressing plate, said shallow chamber being used for two purposes, to wit, for supplying steam or moisture to the work or 25 for withdrawing steam or moisture therefrom, thereby enabling both the steaming and vacuum or suction effects to be quickly and efficiently secured.

Further objects of the invention are in 30 part obvious and in part will appear more in detail hereinafter.

The invention comprises the construction and arrangements of parts hereinafter described and claimed. The present application is a division of my prior application 35 for garment press filed June 7, 1916, Serial No. 102,296, patented Feb. 15, 1921, and bearing number 1,368,684.

In the drawings, which illustrate only 40 those parts of the machine of my prior application, Serial No. 102,296 which are necessary or are involved in the invention forming the subject matter of the present application, Fig. 1 is a side elevation, showing the press open; Fig. 2 is a front view, partly in section, showing the press closed; and Fig. 3 is a detail sectional elevation on a larger scale, on the line 3—3, Fig. 1.

1 represents the frame of the machine, 45 which may be of any suitable or preferred form and which supports the lower pressing

member or garment support 2 carried by a hollow pedestal 3, and which frame is also provided with a pillar or support 4 to which is pivoted at 5 a swinging lever 6 the front 55 arm of which supports the upper pressing member or head 7 and the rear arm of which may be provided with a counterweight 8. 9 represents a tension spring or springs to assist the counterweight in returning the 60 lever 6 to its normal position when the press is opened.

The swinging lever 6 may be operated by any suitable mechanism the drawings showing for this purpose a suitable pivoted 65 treadle 10 connected by a link 11 to one arm of a lever 12 pivoted at 13 in the frame, the other arm of said lever being connected by a link 14 to the pivot 15 between a pair of toggle members 16, 17, of which member 70 16 is connected to the lever 6 and member 17 to a suitable relatively fixed lower support. As illustrated in the drawings and as shown in my prior application before referred to member 17 is pivoted at 18 to a third toggle 75 member 19 pivoted in turn at 20 to the fixed frame, and which third toggle member is provided with an arm 21 which is actuated by power means for producing additional heavy pressure between the pressing members—heavier pressure than is ordinarily produced by the operator in his usual operation of the foot treadle 10. As said power mechanism forms no part of the present invention it need not be further referred to, 80 it being sufficient to state that when treadle 10 is depressed the lever 12 is rocked and toggle links 16, 17 are straightened to bring the head down into pressing relation with the bed and produce sufficient pressure upon 85 the work in pressing position upon the bed to press the same.

The head 7 may be of any suitable form, its particular construction being immaterial, and is illustrated as of the same form shown 90 in said prior application.

The bed garment support or lower pressing member 2 is supported by the hollow pedestal 3 which is provided with an inner cavity 22 supplied with steam in any suitable manner, said cavity being bounded at its top by a horizontal wall 23 of the cast- 100

ing so that a shallow portion 24 of the steam cavity 22 extends beneath the wall 23 throughout the entire area of the bed. Above the wall 23 the casting is provided with longitudinally extending channels 25 in its upper surface, said channels opening into a shallow chamber 26 extending over substantially the entire area of the bed beneath a perforated plate 27 secured to the bed and which is usually covered with suitable padding 28.

Chamber 26 has two functions. First, it serves as the steaming chamber by means of which steam may be distributed to all of the perforations of the plate 27 and thereby discharged upon the work lying upon the bed, and, second, it also serves as the means by which steam or moisture in the padding or work or between the pressing members may be withdrawn to quickly dry the padding and work.

The flow of steam to chamber 26 is controlled by a valve member 29 normally seated by a compression spring 30 and closing a passage 31 having two branches 32 leading to the channels 25, the flow of steam to the passage 31 being from the cavity 22 by way of ports 33. Valve 29 is actuated by a rod 34 connected at its lower end to a treadle 35 pivoted at 36 in the frame. Said treadle may be depressed at any time when the press is either closed or open to distribute live steam from the heating cavity over the entire area of plate 27 and discharge it upon the work.

The vacuum valve may be of any suitable form and as shown comprises a plate 37 seating downwardly and normally closing communication from the chamber 26 to a passage 38 communicating with a pipe 39 leading to a suitable source of suction or vacuum. Said valve is connected to a valve rod 40 passing out through an L 41 in the pipe 39 and suitably connected to operating mechanism. As illustrated said rod is provided with a collar 42 forming an abutment for a compression spring 43 lying above a forked arm 44 of a bell crank lever pivoted at 45 in a bracket of the frame, the other arm 46 of said lever being connected by a link 47 to an arm 48 of the release treadle 49, which is normally raised by a compression spring 50 and, if desired, by a counterweight 51.

Treadle 49 is the release treadle of the machine. In other words, if the press is closed by operation of member 21 so as to produce heavy pressure upon the work actuation of said treadle 49 initiates the releasing operation which opens the press. The mechanism for performing this releasing function forms no part of the present invention and therefore has not been illustrated or described. It is only necessary to state that whenever treadle 49 is depressed

either to release the press, or at any time when the press is open, the vacuum valve 37 is raised from its seat so as to establish communication between chamber 26 and the source of suction, thereby withdrawing through the perforated plate 27 any moisture in or around the work or padding and any steam in the chamber 26.

With the arrangement described the shallow chamber 26 enables the heating effect of the live steam in cavity 22 to be transmitted continuously and quickly to the plate 27 and padding 28 and any work upon the bed. The padding of the bed is therefore always kept heated and is not likely to collect moisture. Both the steam and vacuum valves are located in close proximity to the chamber 26. As a consequence, when the valve 29 is opened steam is admitted directly from the source, to wit, cavity 22, to the chamber 26, and therefore the steam is distributed very rapidly and discharged quickly through the padding to the work. Likewise, the valve 37 is in close proximity to chamber 26, actually lying within a portion thereof, so that when said vacuum valve is opened any moisture is immediately withdrawn. The two effects, to wit, steam and suction are therefore produced very quickly and by a simple arrangement which does not interfere in the least with proper heating of the bed.

What I claim is:

1. A pressing machine comprising relatively movable pressing members, one of said members being adapted to support a garment during the pressing operation and being provided with a chamber, a foraminous member forming the wall of said chamber adjacent the position of the garment while the garment is in pressing position, means for supplying steam directly to said chamber, and valves located in close proximity to and on the same side of the garment as said chamber and opening directly into such chamber for controlling the supply and removal of steam to and from said chamber.

2. A pressing machine comprising relatively movable pressing members, one of said members being adapted to support a garment during the pressing operation and being provided with a chamber, a foraminous member forming the wall of said chamber adjacent the position of the garment while the garment is in pressing position, means for supplying steam directly to said chamber, valves located in close proximity to and on the same side of the garment as said chamber and opening directly into such chamber for controlling the supply and removal of steam to and from said chamber, said garment supporting member being provided also with a steam cavity adjacent said chamber for heating the same, and means for supplying steam to said cavity.

3. A pressing machine comprising relatively movable pressing members, one of said members being adapted to support a garment during the pressing operation and being provided with a chamber, a foraminous member forming the wall of said chamber adjacent the position of the garment while the garment is in pressing position, means for supplying steam directly to said chamber, valves located in close proximity to and on the same side of the garment as said chamber and opening directly into such chamber for controlling the supply and removal of steam to and from said chamber, said garment supporting member being provided also with a steam cavity adjacent said chamber for supplying steam thereto and to said chamber, said valves permitting the removal of steam from the chamber while retaining the steam in the steam cavity, and means for supplying steam to said cavity.
- 10 In testimony whereof I affix my signature.

WILLIAM E. ANDRÉE.
